MULTIPANE WINDOW SASH

George H. Bugenhagen, Midland, Mich.

Application January 12, 1946, Serial No. 640,835

3 Claims. (Cl. 20—56.5)

1

The invention relates to multipane window construction with a sealed air space between each pane of the transparent medium. It more particularly concerns a sash for glass windows wherein two or more panes of glass may be superposed on each other with a sealed dead air space therebetween. It is, therefore, an object of the invention to provide a window sash adapted to accommodate more than one pane of glass in superposed relation with a sealed air space therebetween.

Another object of the invention is to provide a metal sash for multipane window construction wherein provision is made for differences in expansion between the metal and the glass.

Another object of the invention is to provide a metal sash with enclosed chambers into which the glass extends and is adapted to slide back and forth during expansion and contraction, said enclosed chambers being partially filled with an elastic cement to effect an air tight seal between the metal parts of the sash and glass.

Still another object of the invention is to provide a cushioning medium within the enclosed chambers in the metal sash contacting the elastic cement so that the elastic cement will be snugly pressed against the glass and the walls of the chambers during expansion and contraction of the glass.

Another object of the invention is to provide a metal sash which can be adjusted to grip the surface of glass panes having some variation in thickness.

Another object of the invention is to provide a metal window sash which may be readily taken apart for removal of broken panes and replacement, or other repair work.

Another object of the invention is to provide a multipane window sash construction in which the cement effecting the seal between the glass pane and the metal sash is protected against exposure to the air.

Another object of the invention is to provide a metal sash in which the abutting joints formed at the corners, or elsewhere, of the sash are sealed against air leakage.

Other objects and advantages of the invention will be apparent when the following description is considered in connection with the accompanying drawing disclosing certain means of carrying out the invention, such disclosed means illustrating, however, but several of various ways in which the principle of the invention may be practiced.

Fig. 1 is a non-detail side elevation of the window sash.

Fig. 2 is a sectional view along lines 2—2 of Fig. 1 looking in the direction of the arrows, showing, however, the sash of Fig. 1 secured to a wooden sill.

5 Fig. 3 is a view along lines 3—3 of Fig. 1, partly in section, looking in the direction of the arrows.

Fig. 4 is an enlarged detail of the corner construction of the sash.

Fig. 5 is a section view along lines 5—5 of Fig. 10 3 showing a corner section, however.

Fig. 6 is a sectional view along lines 6—6 of Fig. 5.

Fig. 7 is a sectional view along lines 7—7 of Fig. 2.

15 Fig. 8 is an enlarged sectional view similar to Fig. 2 showing, however, a modification of the invention.

Referring to Fig. 1, a metal frame designated generally by numeral 1 supports the glass pane 2.

20 As seen more clearly in Fig. 2 the metal sash 1 abuts or is seated on the wood sill 3 at 4 and is retained or held securely thereto by means of clip 5 and screws 6. The metal frame itself is a hollow composite structure and is formed so 25 as to have two identical chambers 7 enclosed by the metal shell and separated from each other by a general U-shaped channel section 8 formed by web members 9 and 10 of the metal shell. Flat headed screws 11 are provided at suitable intervals along the metal frame and extend from the back face 12 of the metal sash to the front face 13 which it engages in threaded relation at 14. The screws 11 serve to pull the two outer lip portions 15 and 16 of the back and front faces 12 and 13 together and thus presses the glass 2

30 against cooperating inner lip members 17 and 18 formed by the extension of webs 9 and 10. The web sections 9 and 10 are conveniently held apart a proper distance by spacers 19 which ride on flat headed screw 11. This construction allows glass panes of different thicknesses to be 35 used in the same sash by virtue of the wide latitude of adjustment afforded by the double web.

As shown, the glass panes 2 extend into the chambers 7 through the slotted openings 20 40 formed along the inner face of the sash. Within the two chambers 7, the glass panes 2 are surrounded by elastic or non-hardening putty 21, which fills the chambers to a point preferably above the ends or edges of the glass panes 2.

45 Flexible strips 22 which are shown in this instance as sponge rubber but might be of any fibrous material of a yieldable nature fill the rest of the chambers 7 and are held in place by reason of their extension over the flat head 50 screws 11. In this manner a sealed or dead air 55

space 23 is maintained between the identical panes of glass 2.

In Fig. 3, the section has been taken at a slightly different point to show screw plugs 24 which act to seal openings 25 provided for the attachment of a putty gun (not shown), whereby addition of elastic putty to the chambers 7 may be readily made.

Referring to Fig. 4, a corner elevation is shown in enlarged detail. The sash 1 is cut at a 45° angle at the corner to form a snug fitting miter joint 26 between the separate sections of the sash. The separate sections are held firmly together by means of bracket 27 which is engaged by screw bolts 28 as seen more clearly in Fig. 5.

In Figs. 5 and 6, the corner construction is shown in enlarged detail. The manner in which the sponge rubber strip 22 is held in place at the top of the chambers 7 by the action of the flat head screws 11 in pressing the sponge rubber strip upwardly against the top of the chamber is seen more clearly in Fig. 5. In order to effect a seal so that air will not escape or enter the dead air space 23 at the miter joint 26, hole 29 is provided through the lower portion of the web sections 9 and 10, seen more clearly in Fig. 6. A portion of the circumference of hole 29 is open to the air through U-shaped channel 8. In this manner air that might follow along the metal at the miter joint 26 and enter the air space 23 is effectively blocked by the sealing action of the putty entering the hole 29. A small amount of putty will squeeze out into the U-shaped channel 8 at the miter joint, but the action of the air will soon harden the surface and stop further loss at this point. It will be apparent that the sash may be made up in four sections or, if desired, only two sections need be used wherein a mitered joint will be used at adjacent corners or at opposite corners.

In the sectional elevational view of Fig. 7, the relation of the wood sill 3, the sash 1, the rubber strip 22, compressing screw 11 and the glass pane 2 is seen in clearer detail.

In the enlarged sectional elevational view of Fig. 8, a modification of the invention is shown. The metal frame 30 is separated into two identical chambers 31 by the metal web 32. The metal web is provided with a thickened section 33 which is tapped and threaded at intervals to accommodate screws 34 extending through from either face in staggered relation. In this manner, the tension of the lip portions 35, 36, 37, and 38 against the glass panes may be readily regulated. Sponge rubber strips 39 are held in place in either chamber 31 by screws 34, and a non-hardening sealing material 40 fills the remainder of the chambers in the manner described in connection with the modification of Figs. 2 and 3.

At the corners or at other points where sections of the metal sash are coupled in abutting relation, it will, of course, be desirable to provide a hole through the web at the point of abutment so that air will be blocked from following along the metal faces of the abutting sections and entering the dead air space. In the modification shown in Fig. 8, it will be apparent that the non-hardening sealing material will be denied access to the air at the mitered joints and thus a different result is obtained than in the case of the modification of Fig. 2. For this reason, modification of Fig. 8 may be more preferable in certain instances. Alternatively, a soft metal gasket or a rubber gasket may be inserted at the point of coupling of the sash sections.

The operation of the invention will be best understood from the following description, wherein in the window is assembled with the frame 1 in four sections. The flat headed screws 11 will be removed while the sponge rubber strips 22 are inserted through the slotted openings 20. Flat headed screws 11 are then inserted with spacer 19 in place and started into threaded engagement at 14 so as to hold the sponge rubber strip 22 in place but without pulling the two faces 12 and 13 together. Bracket 27 is then attached and two sections are fastened together thereby. Thereafter, the panes of glass 2 may be suitably inserted through the slotted openings 20 in the partially assembled sash and, after the position of the glass pane is suitably adjusted, screws 11 will be taken up until the glass panes are snugly engaged by the lips 15, 17, 16, and 18, respectively, of the two sections. Thereafter, another section of frame 1 may be added and secured in place by a bracket 27, or, if desired, two more sections may be made up as described above and added as a unit. In any case, when the frame is completely assembled and screws 11 have been suitably tightened to hold the glass panes securely in place, the non-hardening putty 21 may be added. In adding the putty, it will be desirable to start at one point and work around the frame 1. For example, the operation of adding the putty 21 may be conveniently started at the bottom of the frame. It will be desirable to remove the adjacent screw plugs 24 and add the putty 21 through one of the holes with a conventional putty gun provided with a fitting adapted to engage the plug hole until the putty can be seen coming out the next hole indicating that the space in chamber 7 between the holes is completely filled. Thereafter, the next plug 24 will be removed and the process repeated until the chambers 7 around the entire sash are completely filled with putty. The window may then be placed in the sill 3 and secured therein by means of retaining clip 5.

Sponge rubber is ideally suited for use in the chamber along with the non-hardening putty, or the like, because any expansion of the glass due to heating will simply force the putty or other similar sealing material up against the rubber. The rubber will readily yield to the force without attendant high pressure such as would be encountered if the entire chamber 7 were filled with fluid. It will be generally desirable to choose a type of sponge rubber such as one of the new synthetics which is unaffected by the sealing material being used. Other materials may be used in the place of rubber. For example, any fibrous yieldable material will serve such as oakum, loose pile fabric, and the like. While the conventional non-hardening putty is very suitable for use in connection with sealing around the edges of the glass panes, other materials may be used such as non-hardening viscous tars or viscous polymers produced by partial polymerization of synthetic resin-forming materials. Many such materials are readily commercially available.

It is to be understood that, while the invention has been described with reference to only two glass panes with a single air space sealed therebetween, it is within the scope of the invention to extend the metal shell to provide one or more additional chambers similar to those shown and other glass panes for any desired number of sealed air spaces. Additionally, while the metal sash has been described as being rectangular in shape to accommodate the usual rectangular panes of glass, it might be conveniently made

circular, oval, or diamond shape without essential modification.

Other modes of applying the principle of my invention may be employed instead of those explained, change being made as regards the mechanism herein disclosed, provided the means stated by any of the following claims or the equivalent of such stated means be employed.

I, therefore, particularly point out and distinctly claim as my invention:

1. In a multipane window sash, the combination which includes a metal shell enclosing two chambers sealed from each other by a metal web, said metal shell having spaced slotted openings along the inner face opening into the chamber adapted to accommodate the edge portions of the glass panes, lip portions integral with the metal shell adjacent the slotted openings adapted to slip over and resiliently grip the edge portions of the glass panes, means to adjust the tension with which the lip portions grip the glass, a sponge rubber strip mounted in each chamber on the wall opposite the slotted openings, a non-hardening putty filling the remainder of said chambers, and coupling means carried by the metal shell adapted to hold sections of the metal shell in abutting relation, said abutting sections having their chambers in communication with each other through the metal web below the sponge rubber strips at the point of abutment.

2. In a multipane window sash construction, the combination which includes a rectangular metal shell enclosing two chambers separated from each other by a metal web, said metal shell having spaced slotted openings along the inner face opening into the chambers adapted to accommodate the edge portions of the glass panes, lip portions integral with the metal shell adjacent the slotted openings adapted to resiliently grip the edge portions of the glass panes, means to adjust the tension with which the lips grip the glass, sponge rubber strips mounted in the chambers on the wall opposite the slotted openings, a non-hardening putty filling the remainder of the chambers, said metal shell having miter joints at the corners, a bracket adapted to reasonably secure the mitered joints in abutting relation, said mitered joints having their cham-

bers in communication with each other through the metal web below the sponge rubber strip at the point the joints abut.

3. In a multipane window sash construction having a sealed air pocket between adjacent panes of glass, the combination which includes a metal shell enclosing two chambers separated from each other by a metal web, said metal shell having spaced slotted openings along the inner face opening into each chamber adapted to accommodate the edge portions of the glass panes, lip portions integral with the metal shell adjacent the slotted openings adapted to slip over and resiliently grip the edge portions of the glass panes, means to adjust the tension with which the lips grip the glass, sponge rubber strips mounted in the chambers on the wall opposite the slotted openings, a non-hardening putty filling the remainder of the chambers, said metal shell having spaced sealable openings communicating with the chambers for insertion of the putty, and coupling means carried by the metal shell adapted to hold sections of the metal shell in abutting relation, said abutting sections of the metal shell having their enclosed chambers in communication with each other through the separating metal web below the sponge rubber strips at the point of abutment.

GEORGE H. BUGENHAGEN.
